Specification for Design.

Patented Oct. 15, 1918.

Application filed August 16, 1918. Serial No. 250,250. Term of patent 7 years.

To all whom it may concern:

Be it known that I, SIDNEY V. JAMES, a citizen of the United States, residing at Niagara Falls, in the county of Niagara and State of New York, have invented a new, original, and ornamental Design for a Handle for a Spoon, Fork, or Similar Article, of which the following is a specification, reference being had to the accompanying drawing, forming part thereof, wherein—

Figure 1 represents an obverse view of a

handle for a spoon, fork or similar article, showing my new design;

Fig. 2, a reverse view; and

Fig. 3, a section on line $x-x$ of Fig. 1.

I claim:

The ornamental design for a handle for a spoon, fork or similar article, as shown.

SIDNEY V. JAMES.
